ROTARY HOOK

Charles F. Rubel, Chicago, Ill., assignor to Union Special Machine Company, Chicago, Ill., a corporation of Illinois

Application April 21, 1937, Serial No. 138,088

10 Claims. (Cl. 112—228)

This invention relates to rotary hooks useful by cooperation with the needles of sewing machines in forming what are commonly known as lockstitch seams.

5 In the usual types of such hooks, the revolving needle loop-seizing or hook component has an internal circumferential groove of square cross section which engages, with a snug working fit, an external circumferential bearing rib of corresponding cross section on the non-revolving bobbin case holder. Thus, during the operation of the sewing machine, excessive heat is generated by friction between the extensive contacting surfaces of the hook groove and the bobbin case 10 holder rib, with the result that very rapid wear of the parts takes place notwithstanding the presence of lubricant, which, of necessity, must be sparingly used to avoid staining or soiling of the thread or of the material being sewed.

15 The purpose of my invention is to overcome the above drawbacks, that is to say, it has for its aim to reduce friction between the relatively rotating parts of the hook to a minimum with a view toward making possible the operation of 20 lockstitch sewing machines at much higher speeds than attainable heretofore and in turn securing a correspondingly increased output from them. These advantages I realize in practice, as hereinafter more fully disclosed, by forming 25 the rib on the bobbin case holder considerably narrower than ordinarily so that it clears the sides of the groove in the rotating hook component and by providing the body of said rotating component at circumferential intervals with recesses for confining bearing balls which engage a 30 conformative peripheral raceway in the rib of said bobbin case holder, and, as a consequence, constitute an annular series of spaced contact points to maintain the rib centralized in the 35 groove.

40 In the drawing,

Fig. I is an axial sectional view of a rotary hook conveniently embodying the present improvements.

45 Fig. II shows the rotating component of the hook in front elevation with the stationary component or bobbin case holder and the bobbin case removed, and with a portion broken away to expose one of the bearing balls.

50 Fig. III is an elevation of the rotating hook component viewed from the left of Fig. II.

Fig. IV shows the front elevation of the bobbin case holder; and

55 Fig. V is an elevation of the bobbin case holder viewed from the right of Fig. IV.

In Figs. I—III of these illustrations the rotating component of my improved rotary hook is comprehensively designated by the numeral 1; the same being shown as having a frontally-open hollow annular body 2 which provides a needle loop seizing beak 3 and a rearwardly projecting axial boss or hub 4 for connection to a drive shaft 5 by means of a plurality of set screws whereof one is indicated at 6. Disposed within the hollow of the rotating component 1 is a non-rotating 10 cylindric bobbin case holder 7 having an external circumferential rib 8 which extends into an internal circumferential groove 9 in the body 2 of the rotating component.

In accordance with my invention, the rib 8 is 15 made considerably narrower than the groove 9 so that it clears the opposite side walls of said groove as shown in Fig. I. Between the rotating and non-rotating components 1 and 7 of the rotary hook, I interpose a series of circumferentially-spaced bearing balls 10 which are confined in cylindric radial cavities 11 in the body 2 of said rotating component and which project somewhat beyond the mouths of the cavities into engagement with a transversely concaved conformative peripheral raceway 12 in the rib 8 of said stationary component. As a consequence of this interengagement between the balls 10 and the raceway 12, the rib 8 of the bobbin case holder 7 is positively maintained centralized in the groove 30 9 of the rotating hook component 1 free of contact with the side walls of said groove. The ball cavities 11, it will be observed from Figs. I and II, are formed jointly by radial openings in the body 2 of the rotating hook component 1 and by segmental backing plates 13 and 14 which are respectively secured by screws 15 and 16 to the periphery of said body and which serve as the backing for the balls 10. In order to provide for retention of the balls 10 by the rotating component 1 of the hook, the edges of the mouths of the cavities 11 are extended inwardly somewhat as shown at 17 in Figs. I and II. The segmental plate 13, may, as illustrated, have the form of a gib with an inwardly extending flange 45 18 adapted to underreach a corresponding segmental extent of the frontal edge of the body 2 of the rotating component 1 and to form a portion of one side wall of the groove 9, and with an end portion 19 suitably shaped to serve as the loop-shedding tail of the rotary hook. The plate 14, on the other hand, may provide the loop-deflecting edge 20 (Fig. III) of the rotary hook, and in conjunction with the beak 3 forms 50 55

the usual thread-receiving notch or throat 21 of the hook.

Except for having a ball raceway 12 at the periphery of its rib 8, the bobbin case holder is of customary construction in that it has a segmental frontal flange 23 with a recess 24 for engagement by the usual detaining or holding finger (not shown) of the sewing machine, and a transverse web or spoke 25 across the back 10 thereof which supports an axial bobbin case mounting stud 26.

The bobbin case indicated at 27 in Fig. I is likewise of standard form and construction for fitment into the hollow of the bobbin case holder 15 7 with its inwardly-extending axial sleeve projection 28 engaging over the stud 26 of said holder and in turn serving as a support for a freely rotatable thread spool or bobbin 29.

Due to the interposition of bearing balls which 20 serve as spaced contact points between the relatively rotating elements of the rotary hook in the manner herein set forth, it is evident that I have reduced friction to a very minimum. My improved rotary hook can thus be operated at 25 much higher speeds than hooks of ordinary construction without danger of overheating or attendant excessive wear of the parts, thereby not only making possible increased production by the sewing machine in which the hook is used, 30 but doing away with the necessity for the frequent replacement of worn parts as heretofore. When required, the bobbin case holder 7 can be withdrawn from the body of the rotating hook component 1 upon removal of the gib 13 and the 35 three balls 10 associated with the latter.

While for the purpose of exemplification herein I have shown six bearing balls, this number is to be regarded as arbitrary since, within the scope of the appended claims, it may be increased 40 or decreased as found desirable or convenient in practice.

Having thus described my invention I claim:

1. A rotary hook for sewing machines comprising a pair of relatively rotating components one 45 within the other; and a series of bearing balls confined in one of said components and projecting into a conformative circumferential raceway in the other component.

2. A rotary hook for sewing machines comprising 50 a rotatable loop seizing component having a hollow annular body portion with an internal circumferential groove; a non-rotating bobbin case holder with a narrower external circumferential rib extending into the groove of the hook member and having a ball raceway at its periphery; and bearing balls confined within circumferentially spaced recesses in the annular body of the rotatable component and engaging the peripheral raceway of the rib on the bobbin 55 case holder to keep said rib centralized in said groove.

3. A rotary hook for sewing machines comprising 60 a rotatable loop seizing component having a hollow annular body portion with an internal circumferential groove; a non-rotating bobbin case holder axially within the body of the rotating component having an external circumferential rib which extends into the groove of said rotatable component; and bearing balls within circumferentially spaced radial cavities in the annular body of the rotating component, the edges of the mouths of said cavities extending inward slightly to retain the bearing balls with portions of the latter projecting and engaging

the periphery of the circumferential rib of the bobbin case holder.

4. A rotary hook for sewing machines comprising 5 a rotatable loop seizing component having a hollow annular body portion with an internal circumferential groove; a non-rotating bobbin case holder axially within the body of the rotatable component having an external circumferential rib extending into the groove of said rotatable component; bearing balls retained within circumferentially-spaced radial openings in the annular body portion of the rotatable component and engaging the periphery of the circumferential rib on the bobbin case holder; and segmental plate members on the body of the rotatable component closing the outer ends of the ball openings and forming a backing for said balls.

5. In a sewing machine, a rotary hook; a bobbin case with its holder held from free rotation within the hook, said holder having a circumferential groove externally thereof; and bearing balls confined for rotation with the hook and engaging the external groove of the bobbin case holder.

6. A rotary hook for sewing machines comprising 25 a pair of relatively rotating components, one within the other; and a circumferential series of universally rotatable balls confined by one of the components, said balls providing changing bearing points for the other component; and 30 means cooperating with the balls for restricting axial play between the two components.

7. A rotary hook for sewing machines comprising 35 a pair of relatively rotating components, one within the other; and universally rotatable balls confined at circumferential intervals by one of said components, said balls providing changing bearing points for the other components; and means cooperating with the balls for restricting axial play between the two components. 40

8. A rotary hook for sewing machines comprising 45 a rotating loop seizing component with a hollow annular body portion; a non-rotating hollow bobbin case holder axially within the body of said rotatable component; a circumferential series of universally rotatable balls confined by 50 the rotating component, said balls providing changing bearing points for the bobbin case holder; and means cooperating with the balls for restricting axial play between said component and said bobbin case holder.

9. A rotary hook for sewing machines comprising 55 a rotating loop seizing component having a hollow annular body portion with an internal circumferential groove; a non-rotating bobbin case holder with an external rib extending into the groove of the rotatable component with provision of clearance at opposite sides thereof; bearing balls confined within circumferentially spaced recesses in the body of the rotatable component, said balls providing changing bearing points for the periphery of the rib on the bobbin case holder; and means cooperating with the balls for restricting axial play of said holder.

10. A rotary hook for sewing machines comprising 65 a pair of relatively rotating components one within the other; a series of balls circumferentially interposed between the two components; means for maintaining the balls in uniformly spaced relation; and means cooperating 70 with the balls to restrict axial play between said components.

CHARLES F. RUBEL.
